UNITED STATES PATENT OFFICE.

GEORGE WASHINGTON COOPER, OF NEW YORK, N. Y.

ADJUSTABLE NECKWEAR.

1,110,187.

Specification of Letters Patent.

Patented Sept. 8, 1914.

Application filed August 18, 1913. Serial No. 704,524.

To all whom it may concern:

Be it known that I, GEORGE W. COOPER, a citizen of the United States, and a resident of the city of New York, borough of Brooklyn, in the county of Kings and State of New York, have invented a new and improved Adjustable Neckwear, of which the following is a full, clear, and exact description.

10 This invention relates to adjustable neckwear in the class of articles of apparel, and primarily the invention consists in the provision of an improved collar or neckband having a novel arrangement of buttonholes 15 to permit the apparel to be properly adjusted to the neck of the wearer before and after the same has been laundered, thus providing against tightening of the neckband or collar due to shrinking and also against enlarging 20 thereof due to stretching.

Specifically, the invention consists in providing a collar or neckband in place of the usual longitudinal buttonhole or slit, with a plurality, preferably two inclined or diagonally arranged buttonholes slanted in the direction toward which strain is exerted, thus providing an adjustment which will obviate the necessity of making quarter size collars and which will permit a neck band 30 to properly fit the neck, to hold a collar firm and in place at all times.

With the above and other objects in view, the invention resides more particularly in the peculiar combination and arrangement 35 of parts which will be illustrated as a preferred embodiment in the accompanying drawings and described in the specification.

Reference is to be had to the accompanying drawings forming a part of this specification, in which similar characters of reference indicate corresponding parts in both 40 the views, and in which—

Figure 1 is a perspective view of a collar provided with buttonholes in accordance 45 with the invention; Fig. 2 is a similar view of a fragmentary portion of a shirt having its neckband also equipped with said arrangement of buttonholes; and Fig. 3 is a face view of a neckband opened out and 50 showing the relative positions of the old style buttonholes and my improved arrangement of buttonholes.

In Fig. 1 of the drawings the invention is shown as applied to a collar 10, the same 55 having the usual rear buttonhole 11 and front buttonhole 12 formed in the usual

locking extension 13. The adjacent coöperating extension 14, in lieu of being provided with the usual longitudinal or horizontal buttonhole or slit, is provided with 60 a plurality, preferably two, inclined or diagonally extended buttonholes or openings 15. In practice these openings are spaced apart one-quarter of an inch and when stitched give an adjustment of practically 65 three-eighths of an inch, thus taking the place of quarter size collars and eliminating strain due to shrinking from laundering.

In devices constructed with a somewhat elongated buttonhole extended lengthwise 70 of the material, provided with intermediate bars formed by cross stitchings, the bars become broken and are therefore objectionable, while in the event of providing spaced vertically extending openings, pull thereon 75 tends to spread the openings and stretch the material on the bias, to bunch the material and prevent accomplishment of the adjustment feature desired to be obtained. In the present invention by placing the openings 80 diagonally, a collar or neckband is designed to permit greater strain than is permitted by the usual buttonhole arrangement and the buttonholes are prevented from spreading when strain is exerted thereon. Also, 85 by reason of the fact that the buttonholes are extended diagonally or slant in the direction in which strain is exerted, the shank of the button will at all times lie at the bottom of the opening and thus make the adjustment permanent and unqualified. 90

In Fig. 2 of the drawings a fragmentary portion 16 of a shirt is illustrated, provided with the usual neck band 17 having the rear buttonhole or opening 18, and at one side 95 of the front portion a buttonhole 19 corresponding to the openings 11 and 12 heretofore described. The neckband at the opposite side of the front opening is provided with a pair of diagonally extended or inclined openings 20 similar to the openings 15, thus providing for the adjustment of the neck band to properly conform to the neck of the wearer. The present construction also obviates the necessity of purchasing a shirt 105 having a neckband which is too large, simply to secure the proper size body or vice versa, and the neckband may be adjusted to secure a perfect fit before and after the apparel is laundered.

The contention might be presented that there being two buttonholes on one side

might possibly throw the center off three-eighths of an inch or more, in accordance with the adjustment claimed. To eliminate this a system of cutting has been devised, as illustrated in Fig. 3 of the drawings, in which the old style buttonholes are indicated by the numeral 21 at the upper or outer side and the numeral 22 at the under side. In practice, the buttonhole 21 is five-eighths of an inch from the free edge of the band while the buttonhole 22 is also five-eighths of an inch from the opposite end or free edge of the band, so that the space between these buttonholes is equi-distantly divided with respect to the rear buttonhole 18, in the old method of cutting. In the new and improved method of cutting buttonholes, the buttonhole 19 is extended outwardly or shifted one-eighth of an inch nearer toward the end of the band, and in lieu of the buttonhole 22 the innermost of the diagonal buttonholes 20 is moved back one-eighth of an inch from the outer end of the buttonhole 22 and the outermost of said diagonal buttonholes is moved outward one-eighth of an inch from the outer end of the buttonhole 22, so that the size of the neckband controlled by the distance between the outer end of the buttonhole 19 and the inner buttonhole 20 remains the same, thus insuring the correct size and fit. An enlargement of the band for adjustment outward is accomplished through the medium of the outer buttonhole 20 which gives an adjustment sufficient to compensate for any shrinkage of the band or collar.

In the old style buttonhole the total strain is exerted at the far end of the buttonhole while the diagonal arrangement so divides the strain that two-thirds of the pull is exerted at the far end of the buttonhole and one-third at the near or inner end, thus effectually preventing the buttonholes from tearing and permitting the holes to be cut in various styles well within the scope of the invention. 45

Having thus described by invention, what I claim as new and desire to secure by Letters Patent is:—

1. A fabric neck-encircling article of apparel having overlapped end portions, one 50 of said end portions being provided with a buttonhole and the other end portion being provided with inclined buttonholes spaced apart in parallel relation and slanted in the direction in which strain is exerted thereon. 55

2. A flexible and washable article of neck-wear having a rear button engaging member and co-operating buttonholes at its end portions, certain of said buttonholes being spaced apart in substantially parallel relation and extended diagonally of the length 60 of the article in the direction in which strain is exerted thereon.

In testimony whereof I have signed my name to this specification in the presence of 65 two subscribing witnesses.

GEORGE WASHINGTON COOPER.
